VARIABLE IMPULSE TRANSMITTER

Werner Koenig, Luzern, Switzerland, assignor to
 Landis & Gyr, A.-G., Zug, Switzerland, a corporation of Switzerland

Application January 8, 1935, Serial No. 829
 In Switzerland January 13, 1934

2 Claims. (Cl. 177—380)

The present invention relates to remote control apparatus and more particularly to a novel and improved apparatus for the transmission of a predetermined, variable number of impulses.

Among the objects of the invention is an arrangement including a plurality of switches each adapted to close a circuit to an individual self locking relay, a normally inoperative impulse generator having the circuit to its electromagnetic driving means completed by any one of the locked relays, a multiple contact counting switch driven proportionally to the number of and by the impulses of the impulse generator and circuit connections between contacts of the individual relays and corresponding contacts of the counting switch for unlocking the locked relay when the counting switch reaches the contact corresponding to the locked relay. Novel means are also provided to reset said latter switch to initial position. These and other objects will be apparent as the accompanying specification is studied in conjunction with the accompanying drawing.

The accompanying drawing, referred to herein and constituting a part hereof, illustrates one embodiment of the invention, and together with the description, serves to explain the principles of the invention.

The single figure of the drawing is a diagrammatic view showing the various parts of the transmitter and their circuit connections.

The present invention has for its object the provision of a novel and improved impulse transmitter which is entirely automatic in its operation once it has been set in operation, and which may be, if desired, automatically placed in operation. A further object is the provision of an improved impulse transmitter in which the impulses are transmitted rapidly, at a uniform frequency, and the number of impulses transmitted is accurately controlled.

In accordance with the illustrative embodiment of the present invention the impulse transmitter comprises an impulse generator, which may be a rotating commutator for more or less rapidly interrupting the current supply, a rotary, multiple contact switch provided with a motor for automatically resetting the switch to its original normal position after it has been moved therefrom, switch advancing means operated by the impulses to advance the switch proportionately to the number of impulses transmitted, a plurality of alternatively operable self-locking contact relays to initiate the generation and trans-

mission of the impulses and to cause continued generation and transmission of impulses and an unlocking relay connected with the contact relays and the rotary switch to unlock the contact relays and thereby stop the generation and transmission of impulses when the rotary switch has been advanced the predetermined amount which corresponds to the contact relay which was operated.

It will be understood that the foregoing general description and the following detailed description as well are exemplary and explanatory of the invention but are not restrictive thereof.

Referring now in detail to the illustrative embodiment of the invention as shown diagrammatically in the accompanying drawing, the apparatus is adapted for operation on alternating current of commercial frequencies which is supplied by the mains 10 and 11. The impulse generator comprises a Ferraris motor having a disc 12 and a magnet winding 13, the disc driving a commutator 15 which interrupts the current supply and thereby generates the impulses.

A plurality of contact relays A, B, C, D and E are provided and each of these relays comprises a solenoid 16 (16a, 16b, etc.), adapted to move an armature 17 which carries the movable contacts 18, 19 and 20, adapted to bridge and close their respective stationary contacts. Any desired number of these contact relays may be provided, depending upon the number of different operations to be performed at the receiving end of the remote control installation, each of the contact relays being adapted to cause the transmission of a different number of impulses.

An automatically reset contact selector is provided and is adapted to be operated by the number of impulses transmitted to the receiver. As embodied, this selector comprises a multiple-contact rotary switch having a ratchet 25 connected to a contact arm 26 which contacts with the stationary contacts 27 (27a, 27b, etc.) which correspond in number to the number of relays provided. Ratchet 25 and contact arm 26 are rotatably mounted on motor shaft 29, and are advanced (clockwise) by operation of the pawl 30 pivotally connected to the pivoted armature 31 which is operated by magnet 32 against the tension of spring 33. For resetting the contact 26 to its original position, shaft 29 is connected to the armature 34 of a light motor, while the windings 35 of the motor are in series with a switch 36 which is opened by the contact arm 26 and is automatically closed by movement of

the arm 26 from its original, normal position. Shaft 29 is provided with an arm 46 projecting radially therefrom to engage a pin 47 on ratchet 25.

- 5 A holding circuit control relay is provided for maintaining closed the other relay circuits until the contact arm 26 has contacted with the proper contact 27 so that generation and transmission of the correct number of impulses is effected.
- 10 This relay comprises a solenoid and its armature 48 serving to open the contacts 41 when this solenoid is energized.

For initiating the operation of the various parts of the apparatus, push buttons or time switches 15 44 may be provided, one for each of the contact relays, and when one of these switches is closed, impulses are transmitted over the conductors 45, the number of impulses corresponding to the particular switch 44 which was closed. That is, 20 switch 44a may cause the transmission of a single impulse; switch 44b may cause three impulses to be transmitted; switch 44c may cause four impulses to be transmitted, switch 44d may cause transmission of seven impulses; while 25 switch 44e may cause transmission of nine impulses. These numbers may be varied, however, as required by the apparatus to be operated at the receiving end.

The various parts described above, are in the 30 illustrative embodiment placed in circuit as follows:

The impulse generating commutator 15 is connected in series with the winding 32 and the conductors 45 and receives its power from the mains 35 10 and 11.

The windings 18 are connected to mains 10 and 11 through the contact 20 of one of the contact relays and upon closure of the relay, the motor disc 12 rotates interrupting the current and simultaneously energizing magnet 32 and transmitting impulses over the conductors 45.

The resetting motor windings 35 are connected to main 11 by conductor 50, and by conductors 51 and 52 and switch 36 to main 10.

45 The holding circuit control relay coil 48 is connected to main 11 by conductor 54, and to contacts 19 by conductors 55 which are arranged in parallel. The other side of contacts 19 are individually connected to their respective switch 50 contacts 27 by conductors 56, while contact arm 26 is connected to main 10 by conductor 57.

At the beginning of the operation, current is supplied to each switch 44 from main 10 through conductor 57, contact arm 26, normal contact 27 55 and conductor 58, and upon closure of one switch 44 is supplied to the corresponding solenoid 16 which is also connected to main 11 by conductor 59. When solenoid 16 is energized, contact 18 is moved to circuit closing position and the solenoid 16 is then energized through conductor 59, contact 18, contact 41 and conductor 60.

Inasmuch as the circuit connections of the contact relays B, C, D, and E are duplicates of the circuit connections for relay A, these will not be 60 described in detail.

In the operation of the illustrative embodiment, the operator closes switch 44a, thereby energizing the solenoid 16a and closing contact switches 18a, 19a and 20a. The closure of these switches

causes motor disc 12 to rotate, generating impulses which are supplied to magnet 32 and to the transmission lines 45. Pawl 30 is reciprocated by each impulse, rotating the contact arm 26 until it contacts with contact 27a and immediately after the first impulse, motor armature 34 begins to rotate, but not as fast as the impulse rotation of the contact arm 26. Upon contact of arm 26 with contact 27a, current is supplied to solenoid 48, breaking switch 41 and releasing armature 47 to stop the motor disc 12. Motor 34 continues to operate and arm 46 on shaft 29 engages pin 47 on ratchet 25 to rotate the ratchet and arm 26 and return them to their original position, thereby causing switch 36 to be opened 15 stopping motor 34.

The operation caused by the other relays is similar except as to the number of impulses transmitted and the contact 27 which causes the impulse transmission to stop.

The invention in its broader aspects is not limited to the specific mechanisms shown and described but departures may be made therefrom within the scope of the accompanying claims without departing from the principles of the invention and without sacrificing its chief advantages.

What I claim is:

1. An impulse transmitter including in combination a rotary multiple contact selector switch 30 having a normal position, an impulse generator and electromagnetic means for driving it, means for advancing the rotary element of the switch proportionally to the number of and by said impulses, means for resetting the switch to its normal position after any movement thereof from its normal position, a plurality of relays each having energizing windings and contacts controlled thereby, a circuit for said electro-magnetic driving means completed by certain of the contacts 35 of any relay when energized, means for initially energizing the winding of each relay, a holding circuit for each relay closed by certain other of its contacts to maintain the relay energized independent of said initial energizing means, electro-magnetic means common to said holding circuits of the relays for opening them, a plurality of circuits for said second electro-magnetic means each respectively including in series certain other contacts of said relays and corresponding contacts of the selector switch in its different positions whereby when the selector switch reaches the contact corresponding to the operated relay, the electro-magnetic means will open its holding circuit and thereby stop the operation of the 50 generator.

2. The structure of claim 1, further characterized by the switch resetting means comprising a motor, a lost motion connection between the motor and the rotary element of the switch 60 whereby the switch is moved in advance of the movement of the motor, a motor switch, means for closing the motor switch by the movement of the rotary switch from normal position and for opening the motor switch when the rotary switch 65 reaches normal position and a circuit for said motor including said motor switch.

WERNER KOENIG.
